CONTAINER AND IMPROVED TOP
THEREFORFrank J. Dolan, Brooklyn, N. Y., assignor to
Joseph M. Price, New York, N. Y.

Application November 6, 1934, Serial No. 751,692

6 Claims. (Cl. 229—5.5)

The present invention relates to containers and embodies, more specifically, an improved container construction of the general type shown in applicant's prior Patents No. 1,443,565 dated 5 January 30, 1923 and No. 1,355,222 dated April 28, 1925. More specifically, the invention relates to the top or cover for a container of the type shown wherein the ring which telescopes over a 10 cooperating portion of the container is provided with a beaded portion against which the head 10 of the top engages.

Under certain conditions the rolled over or beaded upper edge of the cylindrical portion of the top has a tendency to unroll or expand causing 15 the elements forming the top to become loosened and thus quickly destroyed. This condition exists particularly when the top is subjected to moisture or when the atmosphere surrounding the top is damp. Under such condition, 20 the bead 9 swells and the effect thereof in holding the head 6 is lost, producing the condition above noted.

An object of the present invention is to provide a top construction, the elements of which 25 are not appreciably affected by moisture.

A further object of the invention is to provide a container top having a beaded upper edge with a head member cooperating therewith in such fashion as to resist any tendency of the bead to 30 unroll or swell.

A further object of the invention is to provide a top of the above character wherein the head portion of the top is formed to engage the bead on the upper edge of the top member frictionally 35 to maintain the same in a predetermined position.

The foregoing objects are attained in the form of the invention described herein by providing a head which is formed with a peripheral groove within which the bead on the top member is received in order that the bead may lie against the 40 surface of the groove and be engaged frictionally thereby.

Further objects, not specifically enumerated above, will be apparent as the invention is described in greater detail in connection with the accompanying drawing, wherein:

Figure 1 is a view in vertical section, taken in a plane passing through the axis of the container, and showing the elements thereof in assembled 50 position.

Figure 2 is an enlarged sectional view of a portion of the top member, showing the formation of the bead and groove in the head to carry out the present invention.

Figure 3 is a view similar to Figure 2, showing the elements in spaced relationship indicating the manner in which they are assembled.

With reference to the above drawing, a container is shown as being formed of a body portion 60 having an outer sleeve 10, the bottom of which

is beaded as shown at 11. A bottom head 12 is adapted to be positioned against the bead 11 and may be held in position by means of an intermediate sleeve 13, the top 14 of which extends above the upper edge of the body member 10 and 5 may be beaded as shown at 15. An inner sleeve 16 may be received within the intermediate sleeve 13, having a covering sheet 17 mounted over the upper end thereof and received between the inner and intermediate sleeves 16 and 13, 10 respectively. The foregoing structure is typical of structures now available on the market and constitutes no part of the present invention.

In order that a serviceable cover may be provided for the body portion of the container above 15 described, a cover construction is formed of the character shown particularly in Figures 2 and 3. This cover is formed of a side member 18 which, if the container is rounded will be of cylindrical shape, the top edge thereof being beaded as 20 shown at 19. Within the cylindrical side member 18, a top head 20 is snugly received, the top head being domed as illustrated in Figure 1, and formed with a peripheral groove 22. Obviously, the material from which the dome is formed may 25 be metal, as well as relatively stiff paper, thus resulting in a greater rigidity than is present in paper containers. The groove is of such size as to receive the bead 19, the surface of the groove being curved to conform to the curve of 30 the bead 19 in order that the adjacent sides of these elements may engage each other frictionally. Moreover, the size of the head is such as to form a snug fit within the side member 18. A liner 23 may be inserted within the side member 35 18 to lie beneath the head 20 and be spaced against the same at its periphery, the size of the liner 23 being such as to be received snugly within the cover in order that its peripheral edge may engage the inner edge of the side member 40 frictionally.

The foregoing structure being forced frictionally into the position shown in Figure 2, provides a cover the elements of which are effectively held in position frictionally. The spring or tension set up in the head and liner 23 by forcing the same within the side member 18 is exerted outwardly against the side member and any pressure exerted on the top of the head member 20 in an endeavor to force the same out of the side member 18 only serves to increase the frictional engagement of these elements. Having a bearing against the inner side of the side member 18 at its peripheral edge, the portion of the top member forming the groove 22 is normally urged upwardly against the lower curved side of the bead 19 to hold the bead effective against swelling and unrolling. Any tendency of the bead to swell or unroll would cause the lower outer curved side thereof to be forced against the curved side of 50 55 60

the groove 22 and thus such action is effectively resisted.

Moreover, in addition to the structural characteristic and advantage gained by the groove construction above described, the appearance of the cover is greatly enhanced in that the effect thereof is that of a flush top cover. Additional advantages flowing from this construction include those of economy and ease of manufacture and 10 assembly, as well as many others which will be apparent to those skilled in the art.

While the invention has been described with specific reference to the accompanying drawing, it is not to be limited save as defined in the appended claims.

I claim as my invention:

1. A container top comprising a substantially rigid side member parallel to the container axis and having an upper edge rolled or beaded inwardly and downwardly from the side member, the rolled portion lying wholly within the plane of the side member, whereby stresses applied outwardly radially of the container against the roll or bead lie in a plane passing through the upper unrolled portion of the side member and are resisted by such upper portion of the side member, and the upper unrolled portion of the side member serves as a substantially rigid backing against which such stresses are applied, and 20 a head formed with a peripheral grooved portion terminating in an edge adapted to fit snugly against the interior of the side member to bow the grooved portion of the head against the bead whereby the outward stress resulting from such 25 bowing action prevents unrolling of the edge of the side member, the grooved portion being adapted to receive the bead of the side member whereby the surface of the grooved portion will be urged upwardly against the adjacent surface 30 of the bead and the edge of the head will be urged outwardly against the inner surface of the side member.

2. A container top comprising a substantially rigid side member parallel to the container axis and having an upper edge rolled or beaded inwardly and downwardly from the side member, the rolled portion lying wholly within the plane of the side member, whereby stresses applied outwardly radially of the container against the roll 45 or bead lie in a plane passing through the upper unrolled portion of the side member and are resisted by such upper portion of the side member, and the upper unrolled portion of the side member serves as a substantially rigid backing against which such stresses are applied, and a domed head formed with a peripheral grooved portion terminating in an edge adapted to fit snugly against the interior of the side member to bow the grooved portion of the head against the bead 50 whereby the outward stress resulting from such bowing action prevents unrolling of the edge of the side member, the grooved portion being adapted to receive the bead of the side member whereby the surface of the grooved portion will be urged upwardly against the adjacent surface 55 of the bead and the edge of the head will be urged outwardly against the inner surface of the side member, and a liner beneath the head engaging the side member frictionally.

3. A container top comprising a substantially rigid side member parallel to the container axis and having an upper edge rolled or beaded inwardly and downwardly from the side member,

the rolled portion lying wholly within the plane of the side member, whereby stresses applied outwardly radially of the container against the roll or bead lie in a plane passing through the upper unrolled portion of the side member and are resisted by such upper portion of the side member, and the upper unrolled portion of the side member serves as a substantially rigid backing against which such stresses are applied, and a head assembly adapted to be inserted into the side wall 10 from the end thereof opposite the bead and having a peripheral portion received frictionally within the member and beneath the bead, the head assembly having means thereon to engage the bead frictionally and being formed to lie substantially flush with the bead whereby the frictional contact of the head assembly with the interior of the substantially rigid side member maintains the bead engaging means in frictional contact with the bead to prevent unrolling of the 20 edge of the side member.

4. A container including a substantially rigid side member parallel to the container axis and having an upper edge rolled or beaded inwardly and downwardly from the side member, the rolled portion lying wholly within the plane of the side member and downwardly from the side member, whereby stresses applied outwardly radially of the container against the roll or bead lie in a plane passing through the upper unrolled portion of the side member and are resisted by such upper portion of the side member, and the upper unrolled portion of the side member serves as a substantially rigid backing against which such stresses are applied, and a head formed with a 30 grooved portion adapted to receive the bead of the side member, the grooved portion terminating in an edge which fits snugly against the interior of the side member to bow the grooved portion of the head against the bead whereby the 35 outward stress resulting from such bowing action prevents unrolling of the edge of the side member.

5. A container top comprising a substantially rigid side member parallel to the container axis and having an upper edge rolled or beaded inwardly and downwardly from the side member, the rolled portion lying wholly within the plane of the side member, and a head adapted to be inserted into the side wall from the end thereof opposite the bead and formed with a peripheral 45 grooved portion opening upwardly to receive the bead and terminating in an edge extending outwardly from the axis of the container and adapted to fit snugly and frictionally against the inner side of the side member below the bead to 50 bow the grooved portion of the head against the bead.

6. A container top comprising a substantially rigid side member parallel to the container axis and having an upper edge rolled or beaded inwardly and downwardly from the side member, the rolled portion lying wholly within the plane of the side member, and a head adapted to be inserted into the side wall from the end thereof opposite the bead and having a peripheral portion received frictionally within the member and beneath the bead, the head being bowed by the side member and having means thereon to engage the bead frictionally whereby the outward stress resulting from such bowing action prevents unrolling of the edge of the side member.

FRANK J. DOLAN.
